[57] **CLAIM**

The ornamental design for a hand tool principally a grout profiler/finisher for use in tiling, as shown and described.

DESCRIPTION

FIG. 1 is a top plan view of the hand tool, principally a grout profiler/finisher for use in tiling

FIG. 2 is a view of one side of the hand tool, principally a grout profiler/finisher for use in tiling, the opposite side view being a mirror image of that shown in FIG. 2;

FIG. 3 is an bottom view of the hand tool, principally a grout profiler/finisher for use in tiling

FIG. 4 is a lateral cross-section through a handle of the hand tool, principally a grout profiler/finisher for use in tiling, the cross-section being taken at a location shown by the arrows 4—4 in FIG. 2;

FIG. 5 is a left end view of the hand tool, principally a grout profiler/finisher for use in tiling; and,

FIG. 6 is a right end view of the hand tool, principally a grout profiler/finisher for use in tiling.
